DRIVE-CHAIN.

1,145,827.

Specification of Letters Patent.

Patented July 6, 1915.

Application filed February 19, 1912. Serial No. 678,583.

To all whom it may concern:

Be it known that I, WARREN J. BELCHER, a citizen of the United States of America, residing at Hartford, in the county of Hartford and State of Connecticut, have invented new and useful Improvements in Drive-Chains, of which the following is a specification.

This invention relates to a drive-chain 10 of the silent, or analogous to the silent, type and the manner of building up such a drive-chain.

Chains have heretofore been made with fiber links which have certain advantages 15 over links made of other material, such as steel. Fiber link chains, however, do not possess all the advantages of the chains made entirely of steel.

It is the object of this invention to combine the use of fiber and metal in the construction of a chain constructed to run on 20 sprocket-wheels so that the advantages of a fiber chain will be retained as well as the advantages of a metal chain, as far as possible.

In the drawings forming part of this application, Figure 1 is a plan view of the skeleton chain made of steel, or other suitable metal, in accordance with one form of 30 the invention. Fig. 2 is a side view of the operative assembled chain as it passes around a suitable sprocket wheel. Fig. 3 is a sectional view on line 3—3, Fig. 2.

The invention, broadly, may be adapted to 35 many of the well known forms of chains constructed to run on sprocket-wheels, for instance the general arrangement of pins and bushings shown in my United States Letters Patent dated March 29, 1910 numbered 40 953,114 may be used, or the unit chain construction disclosed in my application for United States Letters Patent filed January 31, 1911, under Serial No. 605,680 and allowed December 28, 1911, as well as others.

45 With whatever form the present invention is used it can be understood from the following description in connection with the accompanying drawings, wherein a simple form of general chain construction is shown.

50 Referring to the drawings, in Fig. 1 *a* and *b* designate the overlapping side plates of the assembled chain. These side plates are made of steel, or other suitable metal, and preferably have the shape of the link 55 plates as may be seen from Fig. 2. The in-

side plates *b* have metal bushings *d* extending to the middle of the pivot-pins *c*. On these bushings and between the side plates, the link plates *h* are assembled. These plates are made of fiber and are assembled on the 60 bushings in a well known manner, as indicated in Fig. 3. Metal pins *c* extend from the outside plates *a* on one side of the chain through the bushings to the outside plates on the other side of the chain (see Fig. 1) 65 and connect the parts of the chain together as a whole. The pins *c* have heads fitting in countersunk holes in the outside plates *a*. This part enables the chain to run readily on a sprocket having side guards. The specific way in which the pins *c* are constructed is immaterial, as long as the chain is held together properly in any of the well known ways.

From an examination of Fig. 2, it will be 75 clear that the side plates *a* and *b* have the same form as the links *h* but they are smaller and therefore do not engage the teeth of the sprocket-wheel *m* being prevented from doing so by the fiber links *h*, 80 shown in engagement with said teeth. The skeleton chain shown in Fig. 1 without the fiber links is an operative chain in itself constructed to run on sprocket-wheels and would operate on the sprocket-wheel *m*. 85 When the skeleton chain is made into a full chain by the addition of the fiber links, the result is in effect two chains combined into one. The fiber links are the only ones which engage the teeth of the sprocket-wheel. The 90 chain, as a whole, is therefore noiseless and possesses all the advantages of a fiber chain. In addition, the metal pins, bushings, and side plates give the requisite strength and lateral support to the fiber chain.

If by any contingency the fiber links are injured or destroyed (in a way which in the ordinary fiber chain would render said chain wholly inoperative) applicant's chain will have the metal links as a reserve chain, and 100 this reserve chain may be used as long as necessary, or until a new chain is obtained. In any event applicant's chain will not be put completely out of commission as soon as the ordinary fiber chain will be, in case of 105 accident.

The side plates *a* and *b* made of metal need not necessarily have the same shape as the fiber links, for any combination of the metal side plates with the metal pins or 110

bushings which will give strength to the fiber chain, and in case of accident act on the sprocket wheel as a reserve chain for the necessary time, will result to the same effect broadly as the specific chain herein described.

What I claim, is:—

A chain for driving toothed sprocket wheels, comprising metal links, and pins on which said links are pivoted to form a complete skeleton strengthening and supporting chain, non metallic links with teeth engag-

ing projections of the silent chain type pivoted on said pins to fill out said skeleton and form a complete chain, all constructed and arranged so that a chain of the silent type is formed in which said projections form the sole driving contacting means with a sprocket. 15

WARREN J. BELCHER.
